Birdora H. White
by Frank D. Thomas, Atto.

UNITED STATES PATENT OFFICE.

BIRDORA H. WHITE, OF CHICAGO, ILLINOIS.

BUCKLE OR CLAMP.

1,378,391.

Specification of Letters Patent. Patented May 17, 1921.

Application filed February 28, 1920. Serial No. 361,964.

To all whom it may concern:

Be it known that I, BIRDORA H. WHITE, a citizen of the United States, residing at Chicago, in the county of Cook and State of Illinois, have invented new and useful Improvements in Buckles or Clamps, of which the following is a full, clear, and exact description.

My invention relates to buckles or clamps for supporting garments, and particularly garments supported through the medium of straps and loops.

The object of my invention is to provide a buckle that can be adjustably attached to a strap, and from which a garment may be supported quickly and easily, which is provided with hooks that can be made to easily and quickly engage loops or eyes in the supported garment, and be as easily and quickly detached therefrom, and which will not tear the same. This I accomplish by the means hereinafter fully described and as particularly pointed out in the claims.

In the drawings:

Figure 1 is a front view of my improved buckle drawn to a greatly enlarged scale.

Fig. 2 is a top view thereof.

Fig. 3 is a side view of the same.

Fig. 4 is a vertical section taken on dotted lines 4, 4, Fig. 2.

My improved buckle comprises two members, one of which consists of an inverted U-shaped frame, the horizontal bar 5 of which has its ends extend vertically downward to form parallel guides 6, 6, the lower ends of which are bent horizontally away from each other for a corresponding distance to form the lower bends 7, 7, of hooks. The remainder of the construction of these hooks is made by bending the outer ends of the bends 7, 7, upward, to form upright portions 8, that are substantially parallel to the lower portions of the guides 6, 6. The upper ends of these portions 8, terminate below the center of length of the guides 6, and are bent forward to form guards 9, 9, that extend in front of the vertical transverse plane of the bar 5 and guides 6, 6, and are then bent toward each other and looped to form terminal eyes 10, 10. The bends 7, 7, are preferably, curved rearwardly so as to conform to the curvature of the form of the body of the wearer against which they are designed to bear, and the terminals 10, 10, of these hooks are provided with eyes so as to prevent tearing the fabric and to facilitate the

passage of the same past said terminals, which said fabric would otherwise do if the terminals ended by abruptly cutting off the same.

The other member of my improved buckle comprises a clamp which consists of a substantially straight horizontally disposed wire cross-bar 11 which extends from in front of one upright 6 to the other upright 6 of the U-shaped supporting-frame and has its ends coiled upward, preferably, for two or three convolutions to form tubes 12, 12, that surround and slide up and down upon the guides 6, 6. The upper ends of the coils extend forward on the inner sides of the guides 6, 6, until they are in the same transverse vertical plane as the center of length of the bar 11 and then are bent in alinement toward each other to form arms and connected to each other either directly or by entering the bore of a metal sleeve 13 to form an upper cross-bar 14. This metal sleeve confines the ends of said arms of the cross-bar 14 and protects the cloth or fabric from the rough and sharp edges of the extremities of said arms.

In operation the strap on the lower ends of which this buckle is suspended extends down under the horizontal cross-bar 5 of the supporting-frame in front of the clamp, and is bent around the cross-bar 11 of said clamp and up in front of the sleeve, 13, thereof. When any weight is put upon the hooks of the supporting-frame, it will be drawn downward and the fabric or strap will be clamped between the sleeve 13 of the clamp and the horizontal bar 5 of the supporting-frame. This strap is shown in dotted lines in Fig. 5 of the drawings, and it will be apparent that at any time it is desired to adjust the buckle on said strap all that will be necessary to do will be to lift the U-shaped frame and then pull upward on the end of the strap so as to adjust the buckle thereon.

The hooks are designed to be engaged by loops 15, as shown in the drawings, substantially as shown in my pending application for buckles filed in the United States Patent Office December 26, 1919, Serial No. 347,256. But one loop substantially as shown in dotted lines in Fig. 1 of the drawings or its equivalent can be used in connection with said hooks. The design of the hooks will greatly facilitate the entrance of the terminals thereof into the loops, or other equivalents in the garment supported there-

by and the sinuous course of the portions of said hooks extending from the bends 7, thereof to retain the loops on the hooks against the accidental removal and yet make the voluntary removal of said loops by the wearer a matter of easy accomplishment.

What I claim as new is:

1. A buckle comprising an inverted U-shaped supporting-frame made of one continuous piece of wire and having the lower ends of the parallel portions bent laterally away from each other and formed into hooks, the ends of which are bent upward, and a clamping member consisting of a lower and an upper horizontal cross-bar connected by tubular guides that are slidably mounted on the vertical portions of said supporting-frame, said clamping member also being made of a continuous piece of wire and the guides of several coils.
2. A buckle comprising an inverted U-shaped supporting-frame made of one continuous piece of metal and having the lower ends of the parallel portions bent laterally away from each other and formed into hooks, the ends of which are bent upward, the extremities of which terminate in a plane in front of the U-shaped portion, and a clamping member consisting of a single piece of metal and comprising two spaced apart horizontal cross-bars the ends of which are connected by tubular guides that are slidably mounted upon the parallel portions of said supporting-frame.
3. A buckle comprising an inverted U-shaped supporting-frame made of one continuous strip of metal and having the lower ends of the parallel portions bent laterally away from each other and formed into hooks, the ends of which are bent upward, the extremities of which are bent horizontally forward to provide guides and terminate in a plane in front of the U-shaped portion, and a clamping member consisting of a single piece of metal and comprising two spaced apart horizontal cross-bars the ends of which are connected by tubular guides that are slidably mounted upon the parallel portions of said supporting-frame.
4. A buckle comprising an inverted U-shaped supporting-frame made of one con-

tinuous strip of wire and having the lower ends of the parallel portions bent laterally away from each other and formed into hooks, the ends of which are bent upward, 55 the extremities of which terminate in a plane in front of the U-shaped portion and point toward each other and are provided with eyes, and a clamping member consisting of a single piece of metal and comprising two spaced apart horizontal cross-bars the ends of which are connected by tubular guides that are slidably mounted upon the parallel portions of said supporting-frame.

5. A buckle comprising an inverted U-shaped supporting-frame made of one continuous strip of wire and having the lower ends of the parallel portions bent laterally away from each other and formed into hooks, the ends of which are bent upward, 70 the extremities of which are bent horizontally forward to provide guides and terminate in a plane in front of the U-shaped portion and point toward each other and are provided with eyes, and a clamping member consisting of a single piece of metal and comprising two spaced apart horizontal guides that are slidably mounted upon the parallel portions of said supporting-frame.

6. A buckle comprising an inverted U-shaped supporting-frame made of a single piece of wire and having the lower ends of its parallel portions bent laterally away from each other to form hooks, the ends of which are bent upward, which latter have 85 the upper ends of their vertically disposed portions bent forward to provide guards, and the forward ends of the latter terminate in lateral extremities that point toward each other, a clamping member consisting of a 90 single piece of wire comprising a lower cross-bar the ends of which are provided with several coils that form guides that are slidably mounted on the parallel branches of the U-shaped portion of the supporting-frame and have their upper ends bent in alignment toward each other, and a sleeve into the ends of which said last mentioned ends enter.

In witness whereof, I have hereunto set 100 my hand this 24th day of February, 1920.

BIRDORA H. WHITE.
